[57] CLAIM

The ornamental design for a utility receptacle cover, as shown and described.

DESCRIPTION

FIG. 1 is a front perspective view of a utility receptacle cover showing a first embodiment of our new design;

FIG. 2 is a top plan view thereof;

FIG. 3 is a bottom plan view thereof;

FIG. 4 is a rear elevational view thereof;

FIG. 5 is a front elevational view thereof;

FIG. 6 is a side elevational view thereof;

FIG. 7 is a front perspective view of a utility receptacle cover showing a second embodiment of our new design;

FIG. 8 is a top plan view thereof;

FIG. 9 is a bottom plan view thereof;

FIG. 10 is a rear elevational view thereof;

FIG. 11 is a front elevational view thereof;

FIG. 12 is a side elevational view thereof;

FIG. 13 is a bottom plan view of either embodiment thereof with a pair of fastening studs shown in broken lines for illustrative purposes only;

FIG. 14 is a side elevational view of either embodiment thereof with a pair of fastening studs shown in broken lines for illustrative purposes only.
